UNITED STATES PATENT OFFICE.

MARION TAYLOR, OF SOUDAN, VIRGINIA.

BACK-BAND BUCKLE AND TRACE-CARRIER.

SPECIFICATION forming part of Letters Patent No. 659,004, dated October 2, 1900.

Application filed July 7, 1900. Serial No. 22,788. (No model.)

To all whom it may concern:

Be it known that I, MARION TAYLOR, a citizen of the United States, residing at Soudan, in the county of Mecklenburg and State of Virginia, have invented certain new and useful Improvements in Back-Band Buckles and Trace-Carriers; and I do hereby declare that the following is a full, clear, and exact description of the same, reference being had to the annexed drawings, making a part of this specification, and to the letters of reference marked thereon.

The present invention has for its object to provide a simple and effective back-band buckle and trace-carrier that may be constructed of two sections only and will possess strength and durability and capable of being manufactured at a comparatively-small cost; and the invention consists in a back-band buckle and trace-carrier constructed substantially as shown in the drawings and herein-after described and claimed.

Figure 1 of the drawings is a front elevation of a portion of a back-band, showing my improved buckle and trace-carrier connected thereto; Fig. 2, a central longitudinal vertical section thereof; Fig. 3, a perspective view of the back plate; Fig. 4, a similar view of the front plate.

In the accompanying drawings, A represents a slotted back plate, and B the slotted front plate, which together constitute the back-band buckle. These plates are constructed with the longitudinal slots *a b*, respectively located near their upper edges and through which the back-band C passes, as shown in Figs. 1 and 2 of the drawings. The plate A is formed with the usual trace-hook *c*, with which the link or ring *d* of the trace engages, as shown in Fig. 1 of the drawings. This plate A differs in construction from the usual back-band-buckle plates in that it has a locking-tongue D to hold the plate B in engagement therewith when the two plates are connected together. This tongue D is integral with the plate A and is stamped therefrom and bent up at a right angle to the plane of the plate, as shown more clearly in Fig. 3 of the drawings. This tongue is on line with the trace-hook *c* and immediately below the slot *a*.

In order to increase the thickness of the bearing-surface which supports the link or ring *d* of the trace, a double thickness of bearing-surface is provided in forming the plate 55 B with a similar hook *e*, the two hooks engaging each other, as shown, thereby providing a reinforce for the hook *c* and increasing the thickness of its wearing-surface.

When the two plates A B are together, the 60 tongue D will extend through the longitudinal slot *b* of the plate B and seat itself in the groove *f* in the lower edge of the slot *b*, thereby holding the two plates A B together and preventing the lateral or sidewise movement 65 of the plates by the shoulders *h* at the extremities of the groove *f*, with which the edges of the tongue D come in contact.

The upper edge of the plate B is notched, as shown at *g*, to better engage the fabric of 70 the back-band C and prevent it from slipping laterally after the buckle has been connected to the back-band by passing the band through the slots *a b* of the plates.

A very simple and effective back-band 75 buckle is provided with only two pieces or sections, dispensing entirely with pivot-pins, clamps, and other separate devices or attachments which would greatly increase the expense of manufacture and detract from its 80 strength and durability.

The tongue D serves the double function in forming a lock for the two plates A B when connected together and preventing them from moving sidewise and also as a keeper for the 85 link or ring *d* of the trace to prevent it from becoming accidentally detached from the trace-hook.

Having now fully described my invention, what I claim as new, and desire to secure by 90 Letters Patent, is—

1. A back-band buckle and trace-carrier, consisting of two slotted plates each having a trace-hook, the front plate having a groove at the lower edge of its slot and the back plate 95 having a tongue at a right angle to the plane thereof, said tongue extending through the slot of said front plate and engaging the groove, substantially as and for the purpose specified.

2. A back-band buckle and trace-carrier, consisting of a slotted front plate having a

trace-hook, a groove at the lower edge of the slot and a notched upper edge, and a slotted back-plate having a tongue extending at a right angle to the plane thereof and passing through the slot of said front plate and engaging the groove, substantially as and for the purpose set forth.

In testimony that I claim the above I have hereunto subscribed my name in the presence of two witnesses.

MARION TAYLOR.
